UNITED STATES PATENT OFFICE

EMIL NELSON, OF PORTLAND, OREGON

WATCHCASE PENDANT

Application filed June 16, 1925, Serial No. 37,534. Renewed December 28, 1927.

My invention relates to watch cases, and has for its object the production of a watch case having a bow that is incorporated with a supporting member in which one or more apertures are provided for auxiliary or independent attachment to it of a watch chain, strap, fob, or the like.

Such attachment is usually made exclusively to the bow which is, by reason of its construction, necessarily more or less insecure. My invention is intended to offer additional or better security for the making of such attachment, and is of special value in watches when used by mechanics or workmen, and which when so used are likely to encounter exposure to rough usage or liability to accident of being pulled or dropped from the pocket or falling from the hand of the user.

What constitutes my invention will be hereinafter specified in detail, and succinctly defined in the appended claim.

In the accompanying drawing,

Figure I is a view of an embodiment of my invention in present preferred form showing in side elevation a watch case and its pendant and bow.

Figure II is a view of the same taken at right angles to the view shown in Figure I.

Referring to the numerals on the drawing, 1 indicates a watch case which may be made of any suitable and preferred material, shape, and dimensions, and which is shown as one provided with a rotatable stem winder or crown 2. The parts 1 and 2 may be of any usual and preferred description.

My invention consists in providing for an ordinary bow 3 a supporting member 4 which is firmly secured to or made part of the watch case after the manner, for example, of the usual pendant.

In its present preferred form, the bow 3 is oblong in contour and provided with oppositely extending hinge lugs 5 and 6, which the shape of the member 4 is made to accommodate snugly and to protect.

Besides provision of the usual bow 3, the member 4 is provided with one or more, preferably by two laterally disposed, apertures 7 and 8 formed in the body of the member 4.

Said apertures may be of any continuous

or broken contour preferred, those of the oval shape illustrated, having their longitudinal axes disposed at oblique angles to each other and to an intermediate diameter of the case, being of a symmetry that is preferable.

The means preferred for connection with the lugs 5 and 6, respectively, consist of standards 9 and 10 extending from the member 4. Those are preferred because they flank the crown 2, and partially encase the same with protective effect.

The supporting member 4 is provided on the outer sides of the respective standards 9 and 10 with alined recesses that are substantially coextensive in length with the lugs 5 and 6 and to which lugs the longitudinal sides of said recesses are juxtaposed. Into those recesses the said lugs are, in assemblage, fitted with the protective effect upon them already indicated, the apertures 7 and 8 being disposed in the member 4 between the axis of the crown 2, and the edges of said member, and between the periphery of the case 1 and the lugs, aforesaid.

In use an ordinary chain or the like may be attached to the bow 3 exclusively, or if preferred the chain may be provided with auxiliary means of attaching it to the defining wall of one or both of the apertures 7—8. If an ordinary chain be used, it may be attached either to the bow 3 or to one or the other of the apertures defined as specified.

What I claim is:

In a watch case, the combination with its body and a supporting member firmly fixed thereto, of standards projecting from the supporting member, a winding crown intermediate the standards, the supporting member having alined recesses on the outer sides of the respective standards, a bow pivoted to the standards by means of oppositely extending hinge lugs provided on the bow that are substantially coextensive in length with said recess and are juxtaposed to and protected by walls defining the length of said recesses.

In testimony whereof, I have hereunto set my hand.

EMIL NELSON.
